INVENTOR
Helen Dryden
BY *Conrad H. Carter*

ATTORNEY

UNITED STATES PATENT OFFICE.

HELEN DRYDEN, OF NEW YORK, N. Y.

THEATRICAL SCENERY.

Application filed January 28, 1925. Serial No. 5,217.

My invention relates to theatrical scenery; and its objects are to simplify the arrangement of stage settings, to effect quick changes of scenery at a minimum of effort, 5 to assemble and rapidly display a sequence of pre-arranged scenes, to assemble and disassemble a stage scene or set while maintaining vertically the sections thereof, to utilize for scenery at different times the 10 front and rear of each section of the set, and to effect re-arrangements and modifications of scenery sets so as to render more effective the operation of the several parts and to cheapen the cost of production. 15 On the theatrical stage it is necessary at times to effect quick changes of scenery and various devices have been employed to effect such results. Such devices, however, are unwieldy and involved, and require much time 20 and labor for their effective operation. In the changing of an ordinary scene set, much time is consumed in locating in proper position and attaching the various sections forming the set and the services of several 25 operators and considerable effort are required in order to effect the changes. Then again, well known arrangements whereby the stage may be revolved or elevated so as to present to the view of the audience another scene are cumbersome, awkward and expensive. 30

In my invention, by bringing in close proximity two co-operating stacks of scenery sections, each rotatably mounted, I am 35 enabled to shift rapidly a considerable number of scenes in sequence. This I accomplish by depicting on each face of the section a scenic representation. The entire arrangement is similar to that of two books 40 placed in juxtaposition so that the edges of the leaves forming the back of the scene will overlap, and the adjacent leaves will form the side sections. By turning the side sections back upon the rear sections a new 45 scene is disclosed, which is completed by the adjacent faces of the pages forming the side sections. By my invention the amount of 50 scenery needed is greatly reduced, the weight of each section is lightened and the shift of the scenes is made quickly and noiselessly with a minimum of effort. There is also a saving over prior constructions in cost of material, transportation, installation, repairs and operation. My invention is especially

adapted to panoramas, pantomimes or ballets where many quick changes of scenic effects are required, or any dramatic representation requiring fantastic or conventionalized scenery. 55

Attention is hereby directed to the drawing, in which similar numerals of designation refer to similar parts throughout the several views.

Figure 1 is a front elevation of a stage showing the utilization of my improved invention; 65

Fig. 2 is a view of one of the posts and rotatable mechanism;

Fig. 3 is a plan view of one of the posts together with adjacent scenery sections forming part of the set; and 70

Fig. 4 is a plan view of the two posts and scenery sections attached thereto, shown in operative position.

Referring to the drawing, the posts 5 and 6 are each vertically mounted upon a base 32, which is preferably secured to the stage 7 by means of lag screws 8 or in any suitable manner. The posts 5 and 6 are each rotatable on their respective bases 32 and each has mounted thereon collars 9 and 10, which are attached thereto by means of set screws 11 and 12 respectively, and rotate therewith. The collars 9 and 10 are so spaced as to admit the ready securing thereto of the sections of scenery, each of which is secured to said collars by means of the angle irons 13, one end of each angle iron extending through an opening 14 in the collar and having a nut 15 engaging with the threaded end 16. The other end of each angle iron 13 passes through an opening in the plate 17 and terminates in the head 18, the plate 17 being attached to the top or bottom edge of the frame of one of the sections. Each of the sections is thus pivotally secured at the inner edge thereof top and bottom by means of these angle irons or links 13. By reason of such mounting each of the sections rotates with the post 5 and 100 can be adjusted in various positions as shown in Fig. 4. Knobs 19 affixed to the base of each section facilitate its movement back and forth on the stage. 95

The assembling and changing of the 105 scenery sets is effected as follows: In Figs. 1 and 4 a scene of an interior is displayed comprising one face of each of the sections

20^A, 20^B, 20^C and 20^D. In Fig. 1 the posts 5 and 6 are exposed and may be seen just below the proscenium arch 31, but if desired may be covered by top curtains or ceilings 5 (not shown). The outer edges of the sections may be covered by the wings or curtains 27, 28, 29 and 30. To change the scene the sections 20^B and 20^C are moved forward and rotated into the positions occupied by 10 20^A and 20^D respectively, which sections are also correspondingly moved outwardly. The sections 21^A and 21^C are then moved forward into the positions formerly occupied by the sections 20^B and 20^C, the posts 5 and 6 being 15 rotated sufficiently for this purpose. By reason of this shift of sections a new scene is displayed comprising the rear faces of sections 20^B and 20^C, and the front faces of 21^B and 21^C. This changing of scenes is repeated until all of the sections attached to 20 the posts 5 and 6 have been utilized. In this manner, a sequence of a considerable number of scenes may be effected, and as is obvious, the scenes may be quickly changed 25 without lowering the curtain or darkening the stage, all that is necessary being for one operator to bring about such change.

While I have described my invention with particular reference to the preferred embodiment shown, I by no means desire so to limit my invention, it being obvious that various changes and modifications could be made without departing from the spirit and purpose of my invention.

35 What I claim and desire to secure by Letters Patent is:

1. A set for theatrical scenes comprising a plurality of upright posts, a plurality of reversible scene sections hingedly mounted 40 on each of said posts, said posts being arranged so that adjacent sections thereof may have their contiguous edges moved in juxtaposition and whereby the scene sections not employed for certain scenic displays may 45 lie in close compact relation, and means permitting said sections to move bodily about the axis of said posts.

2. A set for theatrical scenery comprising 50 a plurality of supports, a plurality of reversible scene sections on each support, each section being pivotally connected intermediate its side edges to its respective support, said supports and sections being so arranged that the side edges of each section on each support 55 may be moved contiguous to and between opposing side edges of other sections on the same and adjacent supports to form a continuous unbroken scene and sequence of scenes.

60 3. A set for theatrical scenery comprising a plurality of supports, a plurality of reversible co-operating scene sections for each support, a loose pivotal connection connecting each scene section with its respective support intermediate the side edges of the

scene section, said supports and sections being so arranged that the side edges of the sections on each support may be moved to juxtaposition with the side edges of other sections to form a continuous unbroken succession of scenes. 70

4. A set for theatrical scenes comprising a plurality of supports, a plurality of reversible co-operative scene sections for each support, each of said sections being pivotally connected intermediate its side edges to its respective support, said supports and sections being so arranged that the side edges of the sections on each support may be moved to juxtaposition with the side edges 80 of other sections to form a continuous unbroken scene, and means permitting the sections of each support to revolve about the axis thereof.

5. A set for theatrical scenery comprising a plurality of vertical posts, a plurality of reversible co-operating scene sections for each post, a loose pivotal connection between each scene section and its respective post and connected to the section intermediate 90 the side edges thereof, and means for permitting the sections of each post to be moved about the axis thereof, said posts and sections being so arranged that the side edges of each section on each post may successively 95 co-operate with adjacent side edges of other sections to form a continuous unbroken scene.

6. A set for theatrical scenes comprising a plurality of supports, a plurality of reversible co-operative scene sections on each support, and links pivoted at one end to said supports and at their other ends to said scene sections whereby the side edges of the sections on each support may co-operate with adjacent side edges of other sections to form a continuous unbroken scene. 100

7. A set for theatrical scenes comprising a plurality of vertically disposed posts, a plurality of reversible co-operating scene 105 sections on each post, and links on the posts and pivotally connected respective to each section intermediate the side edges thereof, whereby the side edges of the sections on each post may be moved contiguous to and 110 between opposing side edges of other sections on the same and adjacent posts to form a continuous unbroken scene, and sequence of scenes. 115

8. A set for theatrical scenes comprising 120 a plurality of vertically disposed posts, a plurality of reversible co-operating scene sections on each post, and links pivoted at one end to said support and at their other ends to said scene sections and means permitting said posts to be rotated whereby the side edges of the sections may be brought in juxtaposition to form a continuous unbroken scene. 125

9. A set for theatrical scenes comprising 130

a plurality of vertically disposed posts, a plurality of reversible co-operating scene sections on each post, and links carried by the posts and pivoted respectively to each section intermediate its side edges, and means permitting said sections to revolve about the axis of their respective supports,

whereby the side edges of the sections on each post may successively co-operate with adjacent side edges of other sections to form a continuous unbroken succession of scenes.

In testimony whereof I have hereunto set my hand this 27th day of January, 1925.

HELEN DRYDEN.
